PAPER STAPLING MACHINE

Theodore Plotkin, Brookline, Mass.

Application May 19, 1953, Serial No. 355,986

11 Claims. (Cl. 1-3)

This invention relates to stapling devices, and more particularly to the small desk type of stapling machines to staple papers and documents.

The conventional desk type of stapling machine consists in general of a vertically movable arm, carrying a magazine and drive mechanism for the staples, attached to a stationary base, which is adapted to be laid on a desk or table and supports the anvil which clinches the ends of the staple. The operator holds the papers to be stapled against the anvil with one hand and presses the movable arm down with the other. The use of both hands for the stapling operation is not a substantial inconvenience if the stapler is used only occasionally. When a number of stapling operations must be performed in rapid succession, however, the necessity of using both hands for each operation becomes burdensome and slows down the work.

The chief object of this invention is to provide a stapling machine which may be readily operated with one hand, so that the user's other hand is free to sort and distribute papers or perform other tasks. Other objects are to produce a machine so operated which is simple in construction and reliable in operation, and which requires no particular skill to manipulate. If desired, the machine may be operated as a conventional stapler using both hands.

The machine consists in general of a frame carrying an inverted stapling head, which may be placed on any flat surface, a swinging arm carrying an anvil, and an intermediate lever carrying a plate on which the papers are placed. The lever is linked to the arm in such a way that pressure of the hand holding the papers against the plate brings the anvil into operating position and operates the stapling head.

In the drawings:

Fig. 1 is a plan view of a stapling device constructed according to the invention,

Fig. 2 is a side view of the device in open position,

Fig. 3 is a side view, partly in cross-section of the device in operating position,

Fig. 4 is an enlarged cross-section along line 4-4 of Fig. 3,

Fig. 5 is an enlarged cross-section along line 5-5 of Fig. 3, and

Fig. 6 is a side view, partly in cross-section showing the staple magazine opened for filling.

The staple drive mechanism is of generally conventional construction but is inverted from the usual position. The mechanism is enclosed in a two piece frame consisting of a lower piece 10 and an upper piece 11, hinged together at the rear by pins 13 and 14. The rear part 12 of frame piece 10 forms a base for the rear part of the stapler. The driving head 15 is slidably mounted in the forwardly extending arm 12a of frame piece 10 and is attached to the presser foot 16 which is spring-pressed outward from the frame by coil spring 17. The upper frame piece carries the magazine 18 in which a block of staples 19 is placed. The staples are pushed forward by a conventional feed mechanism consisting of a slide 20

2

having a hook 21 to which a tension spring 22 is connected. The spring is carried forward around a pin 23 which bears against a latch bar 24 slidably mounted in arm 12a. A pair of lugs 25 extending downward from frame piece 11 have notches 26 which are engaged by the latch bar 24 when the frame is closed. The latch bar may be disengaged to open the frame for loading as shown in Fig. 6. A guide channel 27 runs the length of the magazine to guide the slide and the staples. The slide is keyed to channel 27 by means of headed studs 20a running through slot 27a in the channel. Drive head 15 carries an ejector plate 28 which pushes a staple out through slot 29 in frame piece 11 when presser foot 16 is pressed toward the frame.

Upper frame piece 11 has a pair of upwardly extending wings 30 and 31 in which are mounted pins 32 and 33. A first lever 34, carrying an anvil 35 is rotatably mounted on pin 32. The anvil has the conventional grooves 36 and 37 (Fig. 4) for clinching the ends of the staple. A hand knob 55 is mounted on the lever above the anvil. A second lever 38 has a pair of upstanding lugs 39 and 51 provided with slots 40 and 41 which ride over pin 33. The forward part of lever 38 is widened to form a bed plate 42 on which papers are laid for stapling. The bed plate has a depending rounded lip 43 which acts as a baffle to prevent insertion of the paper into the wrong opening, and is provided with a central opening 50 large enough to admit the anvil 35 and clear the end of frame piece 11.

Lever 38 carries a pair of upstanding lugs 44 and 55 which are rotatably connected to lever 34 by means of a pin 46. Mounted under lever 38 are two leaf springs 47 and 48. Spring 47 tends to push the lever 38 in the clockwise direction (as viewed in Figs. 2 and 3) about pin 33, and spring 48 pushes the inner end of the lever upward to the limit of slots 40 and 41. A projection 49 on lever 34 bears against lever 38 when the levers are in the position shown in Fig. 2 and acts as a stop to limit the upward travel of both levers.

To operate the device, the papers to be stapled (52 in Fig. 3) are placed on the bed plate 42. The operator then presses down on the bed plate, rotating lever 38 counterclockwise (as viewed in Figs. 2 and 3) about pin 33. It is immaterial whether the operator presses on the front part of the plate or to one side, as presser foot 16 is wide enough to prevent tipping. The motion of plate 42 is transmitted to lever 34 through the connection at pin 46. Because of the arrangement of the linkage, lever 34 travels more rapidly than lever 38. By the time lever 38 has moved downward sufficiently to allow the forward end of frame piece 11 to come in contact with the under side of the paper, anvil 35 will be in contact with the upper side of the paper, as shown in Fig. 3. At this point, a rise 53 on lever 38 engages the under side of lever 34 preventing further relative movement of the levers, except that the clearance provided by slots 40 and 41 allows for a certain amount of further adjustment between anvil 35 and the face of plate 42 according to the thickness of the group of papers introduced. It is clear that further downward pressure on plate 42 will depress the forward end of frame piece 11 and operate the driving head 15 to drive a staple through the paper against anvil 35. When the pressure is released spring 17 restores the driving head to its idle position, and springs 47 and 48 return the levers to the position shown in Fig. 2.

The stapler allows an operator to staple papers together rapidly and easily using one hand both to hold the papers and to operate the machine. This type of operation frees the operator's other hand for sorting and additional tasks and also is an advantage when the machine is used on a store counter or elsewhere where it cannot be readily reached with both hands. The device thus provides the

advantages of the more cumbersome and expensive automatic type of stapling machine, but requires no electric attachments and occupies no more space than the conventional desk type of stapler. The machine may be readily picked up and opened for loading as shown in Fig. 6. It is understood that the device may be more conveniently loaded when held upside down.

The machine will operate side wise as well as vertically. For example, base 12 may be screwed or otherwise fastened to a wall, and plate 42 pushed toward the wall to operate the anvil and driving head.

If desired, the operator may use the machine in the same manner as a conventional stapler, holding the papers on plate 42 with one hand and pressing down on hand knob 55 to actuate the driving head.

What is claimed is:

1. A device for applying staples comprising a body, having a base portion adapted to rest on a supporting surface and an arm projecting from said base; a magazine for staples mounted on said body; a staple driving head mounted on said arm and slidable with respect thereto in a direction generally perpendicular to said surface; means for feeding staples in said magazine one at a time to said head; a foot attached to said head and adapted to engage said supporting surface; a first lever connected to said magazine adjacent said base portion and swingable toward and away from said supporting surface; an anvil mounted on said first lever and adapted to cooperate with said driving head to drive and clinch a staple; a second lever connected to said magazine adjacent said base portion and swingable in the same direction as said first lever, said second lever having a plate disposed between said head and said anvil, and the plate having an opening adapted to admit said anvil; and a linkage connecting said levers and adapted to carry said anvil into cooperation with said driving head when said plate is moved toward said surface.

2. A device for applying staples comprising: a body, having a base portion adapted to rest on a supporting surface and an arm projecting from said base portion; a magazine for staples mounted on said body; a first lever mounted on said magazine adjacent said base portion, said first lever being swingable toward and away from said surface; a second lever mounted on said magazine adjacent said base portion and swingable in the same direction as said first lever; a linkage connecting said levers and adapted to produce motion of said first lever toward said surface when the second lever is so moved; and cooperating staple driving members carried by said first lever and said arm and operable by movement of said second lever toward said surface to drive and clinch a staple.

3. A device as described in claim 2, said second lever having a plate disposed between said first lever and said arm and spaced from the latter, and the plate having a lip projecting toward said arm.

4. A device for applying staples comprising: a body, having a base portion adapted to rest on a supporting surface and an arm projecting from said base portion; a magazine for staples mounted on said body; a first lever mounted on said magazine adjacent said base portion, said first lever being swingable toward and away from said surface; a second lever mounted on said magazine adjacent said base portion and swingable in the same direction as said first lever; a linkage connecting said levers and adapted to produce motion of said first lever toward said surface when the second lever is so moved; a spring adapted to urge said levers away from said surface; and cooperating staple driving members carried by said first lever and said arm and operable by movement of said second lever toward said surface to drive and clinch a staple.

5. A device as described in claim 4, having a first stop

means for limiting the travel of said levers away from said surface, and a second stop means for limiting the relative motion of said levers with respect to each other in the direction toward said surface.

6. In a stapler of the type having supporting means with a portion adapted to engage a supporting surface, and a staple driving member slidably received in the supporting means; a first lever connected to said supporting means, and swingable toward and away from said surface; a second lever connected to said supporting means and swingable in the same direction as said first lever; and a linkage connecting said levers and adapted to move said first lever toward said surface when the second lever is so moved, and a staple clinching member mounted on said first lever and disposed to be brought into operative relationship with said driving member by movement of said first lever toward said surface, said driving member having means adapted to engage said surface, and being slidable toward said clinching member.

7. A device as described in claim 6, said second lever having a plate, adapted to support articles to be stapled, disposed between said clinching member and said driving member and having an opening adapted to admit said driving and clinching members.

8. In a stapler of the type having supporting means with forward and rear ends, and a staple driving member slidably received in said supporting means adjacent said forward end; a first lever connected to said supporting means and having a fulcrum thereon adjacent but spaced from said rear end, said first lever being swingable toward and away from said driving member; a second lever connected to said supporting means and having a fulcrum thereon nearer said rear end than the fulcrum of said first lever, said second lever being disposed between said first lever and said supporting means and swingable in the same direction as said first lever; a link connecting said levers together at a point further from said rear end than their respective fulcrums, whereby said first lever is moved toward said driving member when the second lever is so moved; and a clinching member mounted on said first lever and disposed to be brought into operative relationship with said driving member by movement of said first lever toward said driving member, the latter being slidable with respect to said supporting means toward and away from said clinching member.

9. A device as described in claim 8, said first lever having a portion extending rearwardly of its fulcrum and disposed to engage said second lever and limit the travel of the two levers away from said driving member, and the second lever having a portion forward of the respective fulcrums of the levers adapted to engage said first lever and limit the travel of the two levers toward said driving member.

10. A device as described in claim 8, said supporting means having a pin serving as the fulcrum of said second lever, and said second lever having a slot in which said pin is engaged to permit sliding movement of said second lever toward and away from said supporting means, and the device having a spring bearing on said second lever adjacent said slot and normally urging said second lever away from said supporting means.

11. A device as described in claim 6, having a first stop means for limiting the travel of said levers away from said surface, and a second stop means for limiting the relative motion of said levers with respect to each other in the direction toward said surface.
